(57) **CLAIM**

The ornamental design for a bottle, as shown and described.

DESCRIPTION

FIG. 1 is a perspective view of a bottle;

FIG. 2 is a front view thereof;

FIG. 3 is a rear view thereof;

FIG. 4 is a left side view thereof;

FIG. 5 is a right side view thereof;

FIG. 6 is top view thereof; and,

FIG. 7 is a bottom view thereof.

The oblique surface shading shown in FIGS. 1-6 indicates portions of the bottle that are transparent or translucent. The details of the opposing side of the bottle seen through the transparent or translucent portions of the bottle have been omitted from FIGS. 2-6 for ease of understanding.

The dot-dash-dot lines represent the bounds of the claimed design. All other broken lines illustrate portions of the bottle that form no part of the claimed design.
